DESIGN FOR A COMBINED THERMOMETER AND PERPETUAL CALENDAR

Nicholas Rispoli, Cleveland, Ohio

Application September 15, 1936, Serial No. 64,870

Term of patent 7 years

To all whom it may concern:

Be it known that I, Nicholas Rispoli, a citizen of the United States of America, residing at Cleveland, in the county of Cuyahoga, State of Ohio, have invented a new, original, and ornamental Design for a Combined Thermometer and Perpetual Calendar, of which the following is a specification, reference being had to the accompanying drawing forming part thereof, wherein:

Figure 1 is a view in front elevation of a com-

bined thermometer and perpetual calendar, showing my new design.

Figure 2 is a plan view.

The printed matter and numerals appearing on Fig. 1 are merely illustrative.

I claim:—

The ornamental design for a combined thermometer and perpetual calendar, as shown and described.

NICHOLAS RISPOLI.
